LAMP SHADE CONSTRUCTION

Filed April 11, 1940

UNITED STATES PATENT OFFICE

2,302,266

LAMP SHADE CONSTRUCTION

Samuel Sher, Chicago, Ill.

Application April 11, 1940, Serial No. 329,074

4 Claims. (Cl. 240—108)

This invention relates to lamp shade construction, and particularly to a novel construction and arrangement of the covering material, and to novel means for securing the covering material of the shade to the frame thereof.

One object of the present invention is to provide novel means for securing the covering material to a lamp shade frame without the extensive use of stitching or the like.

Another object of the invention is to provide a novel construction and arrangement in a lamp shade cover to facilitate the fitting of the covering material of the shade structure to the frame thereof.

Another object of the invention is to provide a novel construction and arrangement of a lamp shade and supporting means therefor.

A further object of the invention is to provide a simple, inexpensive, and efficient arrangement to facilitate the securing of the covering material to a lamp shade frame in a minimum amount of time.

A still further object of the invention is to improve devices of the character described in sundry details hereinafter referred to and particularly pointed out in the appended claims.

One embodiment of the present invention is shown for illustrative purposes in the drawing, in which:

Fig. 1 is an elevational view of a lamp shade structure embodying features of the present invention, a portion of the shade structure being broken away to better illustrate the construction thereof;

Fig. 2 is an enlarged sectional elevational view of the structure illustrated in Fig. 1, and taken substantially as indicated by the line 2—2 thereof;

Fig. 3 is an enlarged fragmentary side elevational view of a portion of the structure illustrated in Figs. 1 and 2;

Fig. 4 is a fragmentary plan view on an intermediate scale of a portion of the structure shown in Figs. 1 to 3, inclusive, and illustrating the manner of securing a supporting bracket thereto;

Fig. 5 is an enlarged fragmentary sectional elevational view of the structure illustrated in Fig. 4, and taken substantially as indicated by the line 5—5 thereof; and

Fig. 6 is a fragmentary elevational view of a portion of the frame cover or covering material, and illustrating the arrangement of the elements employed in the construction thereof.

In the drawing, the present invention is illustrated as applied to a lamp shade construction shown, in the present instance, as comprising a frame having an upper frame member indicated by the numeral 11 and a lower frame member 12 connected together and laterally spaced apart by means shown, in the present instance, as a

plurality of rods 13 positioned at intervals around the shade structure, the shade when finished including a covering material indicated, as a whole, by the numeral 14, and adapted to surround and cover the frame members 11 and 12 and the rods 13, the upper portion of the shade member being finished off with a strip of braid 15, or other suitable trim, as illustrated in Fig. 1.

It will be noted by reference to Figs. 1 and 2 that the lower frame member 12 is of substantially greater diameter than the upper frame member 11 and, as clearly illustrated in Figs. 2 and 6, the covering material or member 14 comprises a pleated outer ply 16 formed, preferably, of an elongated strip of fabric or the like, having a strip 17 of ordinary tape secured adjacent a longitudinal edge portion 18 thereof by stitching 19, and provided adjacent its opposite longitudinal edge portion 21 with a strip 22 of bias tape secured thereto, preferably, by means of adhesive on one side of the tape 22, thereby providing a structure whereby a degree of elasticity is obtained along the last-mentioned edge portion 21 of the ply 16 to permit of elongating the edge portion 21 to surround the frame member 12 and provide a uniform distribution and taper of the pleats on the outer ply surrounding the frame, as illustrated in Fig. 1.

After the length of the edge portion 21 has been determined according to the circumferential dimension of the frame member 12, one edge portion of a preferably plain inner ply or lining 23 is secured to the edge portion 21 and the bias tape 22, preferably, by means of stitching 24, and the opposite edge portion of the plain ply or lining 23 is folded back upon itself and stitched, as indicated at 25, to provide a loop adapted to receive an annular, resilient, hoop-like retaining ring or member 26 shown, in the present instance, as having an inner diametrical dimension somewhat less than the outside dimension of the upper frame member 11.

For readily securing the covering member 14 to the lamp shade frame in a minimum of time, the ring or retaining member 26, with the edge portion of the inner ply or lining 23 secured thereto, is slipped over the upper frame member 11 in a manner to position the ring 26 outside the frame and between the upper and lower frame members 11 and 12, respectively, as clearly illustrated in Fig. 2, it being understood, that to accomplish this, one side of the ring 26 may be positioned well under one side of the upper frame member 11, due to the wide spacing of the bars 13, and the ring 26 sprung outwardly over the widest portion of the member 11, after which the ring 26 may be positioned with reference to the frame member 11 in the manner shown in Figs. 2 and 5.

The inner ply or lining 23 is then passed over

the upper frame member 11 and down along the inner side of the frame and around the lower frame member 12, adjacent which the bias taped edge portion 21 of the pleated outer ply 16 is positioned, the outer ply 16 being adapted to extend upwardly on the outer side of the lamp shade frame in a manner to position the opposite edge portion 18 of the pleated ply 16 adjacent the looped edge portion of the inner ply 23 and the upper frame member 11 where it is secured in such position by means of long stitches 27 passing through the tape 17, pleated ply 16, looped edge portion of the inner ply or lining 23, and a winding 28 of tape or other suitable material surrounding the upper frame member 11.

It will be observed that by such an arrangement, the covering material may be readily and quickly applied to the frame of the lamp shade merely by slipping the hoop-like retaining ring or member 26 over and around the upper edge portion of the shade frame and passing the covering material downwardly inside the frame and around the lower frame member 12, thence upwardly on the outer side of the frame and secured to the frame member 11 by the long stitches 27, it being understood that by reason of the elasticity of the bias tape 22, the lower edge portion 21 of the pleated ply 16 may be stretched or extended to completely surround the larger frame member 12 to position the pleats uniformly around the frame member at both top and bottom and provide a uniform taper of the pleats toward the upper portion of the shade.

For suitably supporting the lamp shade structure on a light fixture or the like (not shown), a bracket having arms, one of which is shown in Figs. 4 and 5 and indicated at 29, provided with a hook portion 31 adapted to overlie and partially surround the upper frame member 11 outside the adjacent folded portion of the inner ply or lining 23 and, preferably, inside the edge portion 18 of the pleated ply 16, as clearly illustrated in Figs. 4 and 5.

It will be observed from the foregoing description that the present invention provides a novel construction and arrangement whereby the covering material may be readily and quickly secured to a lamp shade frame with a minimum of stitching, and wherein the covering material is so constructed as to facilitate the fitting of the covering material of a shade structure to the frame.

Also, that the present invention provides a novel construction and arrangement whereby a supporting means may be applied to the shade structure after the covering material has been positioned thereon.

Obviously, the present invention is not limited to the precise construction and arrangement shown and described as the same may be variously modified. Moreover, all the features of the invention need not be used conjointly as the same may be used to advantage in variously different combinations and sub-combinations.

What I claim as new and desire to secure by Letters Patent is:

1. In a lamp shade and in combination, a frame comprising upper and lower frame members relatively fixed in spaced relation with respect to each other, an endless substantially rigid hoop-like member surrounding said frame ad-

5 jacent one of said frame members, a covering material having one of its edge portions secured to said hoop-like member and extending around said frame members, and means for securing the opposite edge portion of said covering material to the frame member adjacent said hoop-like member.

10 2. In a lamp shade and in combination, a frame comprising upper and lower frame members relatively fixed in spaced relation with respect to each other, an endless wire hoop-like member surrounding said frame between said spaced frame members and adjacent one of said frame members, said hoop-like member having an inside diameter of lesser dimension than the outer diameter of said adjacent frame member, a covering material having one of its edge portions secured to said hoop-like member and extending around said frame member, and means 15 for securing the opposite edge portion of said covering material to the frame member adjacent said hoop-like member.

20 3. In a lamp shade and in combination, a frame comprising upper and lower frame members relatively fixed in spaced relation with respect to each other, an endless wire hoop-like member surrounding said frame between said spaced members and adjacent one of the frame members, said hoop-like member having an inside diameter of lesser dimension than the outer diameter of said adjacent frame member, a covering material having one of its edge portions secured to said hoop-like member and extending over said adjacent frame member, thence along the inner side of said frame, around the other of said frame members, thence along the outer side of said frame to adjacent said hoop-like member, and means for securing the opposite edge portion of the covering material to the frame member adjacent said hoop-like member.

25 4. In a lamp shade and in combination, a frame comprising an upper annular frame member having a winding thereon and a lower annular frame member spaced laterally therefrom and of greater diameter than said upper member, means for securing said frame members in spaced relation, an annular hoop-like retaining member having an inside diameter of less dimension than the outer diameter of said upper frame member and positioned adjacent thereto between said upper and lower frame members, a cover member comprising an inner lining portion having one of its longitudinal edge portions secured to said retaining member at the outer side of said frame and extending over said upper frame member and thence downwardly on the inner side of the frame to adjacent the lower frame member thereof, said cover member including an outer pleated portion having a strip of adhesive bias tape secured adjacent one longitudinal edge portion thereof and secured under tension together with the adjacent edge of said outer pleated portion to the lower edge of said inner lining portion adjacent said lower frame member, and means for securing the opposite longitudinal edge of said pleated portion to the edge portion of the lining secured to said retaining member and to the winding on said upper frame member.

SAMUEL SHER.
